UNITED STATES PATENT OFFICE.

EDWARD W. STOLER, OF MANSFIELD, OHIO.

WIRE SPOKE.

Application filed December 4, 1924. Serial No. 753,898.

To all whom it may concern:

Be it known that EDWARD W. STOLER, a citizen of the United States of America, residing at Mansfield, in the county of Rich-
5 land and State of Ohio, has invented cer-
tain new and useful Improvements in Wire
Spokes, of which the following is a speci-
fication.

This invention relates to an improvement
10 in spokes designed for use in wire wheels
and the like, and is particularly directed to
a method of forming the spoke to permit
its yielding under load strains in a man-
ner to avoid breakage.

15 The invention relates to an improvement
in the type, character and embodiment of
spoke shown and described in the applica-
tion for Letters Patent filed by Edward
W. Stoler, entitled "Improvements in wire
20 spokes" on April 17th, 1923, Serial No.
632,680.

By experiment the creation of, and actual
reduction to practice of the herein described
spoke, it has been found by the inventor
25 that the particular form of spokes shown
in the drawing (in the present invention)
give more efficiency in their operation in
actual reduction to practice than the ordinary
spokes because they are permitted to
30 yield in any direction at a predetermined
point of least resistance and also provides
means when the spokes are interlaced in
overlapping relation to another and secured
to the hub and the rim, whereby said inter-
35 lacing of the spokes can be accomplished
without strain or binding effect in crossing
each other or in other words provide means
for clearance between the spokes.

It also has been found that the greatest
40 efficiency in the formation of a spoke is
provided by running the taper from the
threaded end gradually toward the headed
end (or straight from the smaller portion
of the spoke) as the spoke retains its resili-
45 ency and is prevented from fracturing and
breaking the larger portion of the tapered
portion adjacent to the threaded end rather
than adjacent to the head portion of the
spoke.

50 It has also been found that to provide
a rounded shoulder at the juncture between
the smallest portion of the tapered portion
and the portion provided with the head pre-
vents fracture, breakage, and undue strain-
55 ing of the spoke at the point where the

spoke yields, that is at the point of least
resistance.

One of the objects of the present invention
is to provide a spoke that will yield
at a predetermined point of least resistance,
80 that is, to so form and produce and con-
struct a spoke that it will yield in the first
instance at the juncture between the small-
est diameter of the tapered portion and the
rounded shouldered portion adjacent to the
85 enlarged portion of the headed end.

A further object is to provide a spoke of
such dimensions, shape, and form that a
plurality of spokes of like character and
construction can be interlaced in overlap-
70 ping relation to each other and secured to
the rim and hub of a wheel to provide clear-
ance between the overlapping spokes to
prevent binding or strain.

Another object is to construct a spoke
75 for wire wheels, that the point of least re-
sistance will be at the juncture of the
smallest diameter of the tapered portion
(or small diameter straight portion) and a
rounded shoulder, which is contiguous with
80 the headed end and with the largest diam-
eter of the tapered portion gradually being
reduced in diameter from a point adjacent
to the threaded portion toward the headed
portion.

85 The spokes shown in the drawing are of
two types, which are substantially the same
as each other, obtaining the same result in
substantially the same way, that is, the
smallest diameter of the tapered portion
90 is located adjacent to the rounded shoul-
dered portion and is contiguous with the
enlarged headed end portion of the spoke.

These and other objects are attained by
the mechanism illustrated in the accom-
panying drawing, in which:

Figure 1 shows a side elevation of a
spoke, showing the larger diameter of the
tapered portion of the spoke running to-
ward the headed end of the spoke to the
center, thence running straight from the
smallest portion of the tapered portion to
the juncture of the rounded shoulder por-
tion, between the tapered portion and the
enlarged head portion.

100 Figure 2 shows a side elevation of a spoke
showing the largest portion of the tapered
portion tapering gradually from the thread-
ed portion toward the head portion to the
juncture between the smallest portion of
110

the tapered portion and the shouldered portion of the head portion.

Figure 3 is a perspective view of a wheel showing the plurality of spokes attached to the hub of the wheel and to the rim, showing the spoke interlaced in overlapping relation to each other to provide for clearance between the spokes at the point where they cross or overlap each other.

10 The construction and method of producing the spoke is as follows:

Referring specifically to Fig. 1, reference numeral 1 indicates the central portion of the new type of spoke, 2 represents the juncture between the smallest diameter of the tapered portion and the shouldered portion 2', which is contiguous with the enlarged headed portion. Reference numeral 3 represents the enlarged portion of 15 the tapered portion of the spoke, 4 the threaded end of the spoke and 5 represents the headed end portion of the spoke.

Referring to Fig. 1, any part of the straight part of the spoke indicated between reference numerals 1 and 2 is adapted to yield in the first instance, which is the portion of least resistance, when the wheel is subjected to pressure.

30 The type shown in Fig. 2 is adapted to yield at the point of least resistance indicated by reference numeral 2.

Figure 2 shows a construction of spoke that is gradually tapered from the point indicated at 3 to the point indicated at 2 35 or juncture between the smallest diameter of the tapered portion and the shouldered portion 2' of the headed portion.

It will be noted that the enlarged portion of the tapered portion is located adjacent 40 to the threaded portion running less in diameter until it merges with the shouldered portion 2' of the headed end of the spoke forming a shoulder between the juncture and the lowest diameter of the tapered portion 45 and enlarged headed portion.

In constructing the spoke tapered, means are provided for clearance between the spokes, when they are secured to the rim and hub in overlapping relation to each 50 other in fabricating the wheel in so far as the spokes are concerned.

It will be observed that the formation of a spoke by the hammering or swaging pressure if the kind and character described 55 provides means of permitting the spokes to clear and yield at the reduced portions preventing binding, fracturing and straining of the fibers and breakage of the spokes.

The construction and method of producing 60 spokes of the character, form, and type herein described relieves the head shank, which enters the hub shell or the wheel, which acts as the driver thereby relieving the head end of all straining at the bent 65 portion and throwing the bow or slight

bend at the reduced portion or points of least resistance nearest the driven end and prevents the bend or headed end of the spoke from becoming crystallized at the head and fracturing or breaking.

70 In the use of the wheel the spokes will flex inwardly and outwardly under recurring load strains and relief therefrom, thereby preventing the resultant breakage at one or the other of the points.

75 The method of forming the spoke of the varying or tapered diameters may be mechanically carried as preferred. However, it is believed that a simple and expeditious manner of securing this result is by swaging through a hammering toward the center from the threaded end, thence straight or continuing the taper to headed portion forming same by a series of hammers arranged in radial lines in a chuck or the like with movements in and out, and by a constant hammering or swaging of about 80 ten thousand blows or more to the minute. This method of swaging is usual and needs 85 no further explanation.

90 The improved spoke is therefore designed for greater life than the ordinary spoke, by providing a weakened portion or point of least resistance remote from the application of pressure, to insure a gradual and maximum curvature when subjected to flexing strains.

95 Attention is called to the fact that because of the rapid, extensive and intensive hammering of the metal to produce and 100 form a spoke by the process herein described the same process will produce superior struts and bracing wires for aeroplanes and the like because the size and weight is reduced in tapering same, while 105 at the same time the tensile strength thereof is increased and maintained because of the amalgamation of the fibers of the metal produced by the intensive hammering process.

110 I claim:

115 1. A wire spoke having enlarged straight end portions of predetermined diameters, one of which is threaded and the other headed, said spoke having a portion adjacent the headed end portion which is of materially less diameter than such end portion to provide a point of least resistance, that portion of the spoke adjacent the threaded end portion, being gradually tapered toward the center of the spoke; thence continuing from the center without increasing its diameter from said center to the enlarged headed and straight end portion.

120 2. A wire spoke having end portions of predetermined diameters, one of which is threaded and the other headed, that portion of the spoke immediately adjacent the headed end portion being of reduced diameter, 125 the remaining length of the spoke between 130

- the end portions being tapered from the threaded end portion to the part of less diameter, such portion of less diameter being positioned relative to the headed end to provide for the interlacing fit of adjacent spokes without contact therewith, whereby each spoke may maintain its direct radial position in the wheel without lateral displacement.
3. A wire spoke having end portions of uniform predetermined diameter, one of which is threaded and the other bent laterally and headed, the intermediate portion of the spoke being gradually tapered through its length to a point immediately adjacent the headed end portion, and continued of minimum diameter from the terminal of the tapered portion to the headed end portion to provide a definite length of least resistance.
4. In a wire spoke provided with end portions of predetermined diameters adjacent to each end, one end of the spoke being threaded and its opposite end having a head formed thereon, said spoke being tapered from a point near the threaded end portion to a point near the end and of less diameter than the end portions, thereby providing on the spoke a predetermined point of least resistance on the spoke adapted to yield when subjected to pressure. 50
5. In a wire spoke, a single unit of predetermined length adapted to be interlaced with a similar spoke, said spoke also being provided with one threaded and straight enlarged end portion, with the opposite end being provided with a straight enlarged end portion and a head, said spoke being tapered from a point adjacent to the threaded portion toward the straight and headed end portion to the center of the spoke, thence continuing from the center without increasing its diameter to the enlarged headed and straight end portion.

In testimony whereof I affix my signature.

EDWARD W. STOLER.
